(57) **CLAIM**

The ornamental design for a tread portion of an automobile tire, as shown and described.

DESCRIPTION

FIG. 1 is a perspective view of the top, front and right side of a tread portion of an automobile tire, it being understood that the tread pattern repeats uniformly throughout the circumference of the tire, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is an enlarged front elevational view thereof; and,

FIG. 7 is an enlarged cross-sectional view thereof taken along the line 7—7 in FIG. 6.

The broken lines in the drawings represent environmental structure only and form no part of the claimed design.
